UNITED STATES PATENT OFFICE.

EDWARD J. SILKMAN, OF BALTIMORE, MARYLAND, ASSIGNOR OF TWO-THIRDS TO GEORGE D. PENNIMAN AND THOMAS K. WORTHINGTON, BOTH OF SAME PLACE.

ELECTRIC TYPE-WRITING MACHINE.

SPECIFICATION forming part of Letters Patent No. 448,271, dated March 17, 1891.

Application filed April 7, 1890. Serial No. 346,944. (No model.)

To all whom it may concern:

Be it known that I, EDWARD J. SILKMAN, a citizen of the United States, residing at Baltimore city, in the State of Maryland, have 5 invented certain new and useful Improvements in Electric Type-Writers, of which the following is a specification.

My invention more especially relates to type-writing machines of a class in which the 10 actuating of a key throws into operation mechanism driven by electro-magnetism, which automatically brings the proper letter into correct position, prints it, and successively imparts the necessary feeding, spacing, 15 and reverse movements of the apparatus so as to print the page.

The object of my invention is to secure a simple, efficient, and easily-manipulated machine, together with other advantages hereinafter set forth.

To carry out the objects of my invention, I preferably arrange the characters, figures, letters, and other symbols employed upon the perimeter of a type-wheel in proper sequence, 25 with the small letters interspaced between the capitals. This type-wheel turns with and slides freely endwise upon a shaft having its bearings in a frame traversing a short distance in bearings on the main frame, so as to 30 cause the type-wheel to reciprocate relatively to the paper-carrying roller. Gears on the type-wheel shaft mesh with racks on another frame having a greater range of reciprocation in bearings on the main frame. When a key 35 is depressed it closes the circuit through actuating mechanism, which draws a reciprocating frame forward, at the same time rotating the wheel to bring the corresponding letter into proper position for printing, and automatically locking it in that position by suitable mechanism. The frame having the greatest reciprocation carries at its forward end a stop-plate oblique or inclined to its line of movement and provided with notches corresponding with stops connected with the finger-keys, which stops are arranged transversely across the machine, so that the range of reciprocation of the frame varies with the key actuated, thus causing the type-wheel to 45 rotate a greater or less distance correspond-

ingly, bringing the desired letter into correct position for printing. The abutting of the stop-plate against the stop thus thrown athwart its line of movement shoves it against a yielding bar connected with a swinging stop 55 which interlocks with the type-wheel and holds it securely while the printing is taking place. When the frame retracts, the stop resumes its normal position, and, after printing, the type-wheel is released by automatic 60 mechanism, so as to be free to turn to bring the next character into its proper position. The type-wheel and its automatic stop are connected with a frame movable laterally by means of an intermittently-movable screw- 65 shaft, which turns during the forward movement of the type-wheel, so as to feed it the proper distance to form the next letter.

The subject-matter claimed is hereinafter specified.

The accompanying drawings represent so much of a machine embodying all my improvements as is necessary to illustrate this subject-matter. Some of these improvements, however, may be used without the others, and 75 in machines differing somewhat in their organization and operation from the parts herein shown, which parts, unless otherwise specified, may be of usual construction.

The key-board end of the machine I call the 80 "front," the printing end the "back." That portion of the machine on the right of a person facing the key-board—the usual operating position—I call the "right," the opposite the "left."

The short unfeathered darts on the section-lines indicate the direction in which the spectator is supposed to be looking. The corresponding darts on the machine indicate the direction of movement of the corresponding 90 parts.

The solid unfeathered arrows indicate the electric circuit through the rear type-wheel carriage, actuating-magnets, or solenoids. The similar dotted arrows indicate the circuit 95 through the corresponding front solenoids. The solid feathered arrows indicate the circuit through the front printing-magnets, the dotted ones that through the rear printing-magnets.

The broken lines in Figure 1 indicate circuit-connections hidden by other mechanism.

Fig. 1 represents a plan or top view of the entire apparatus in its normal position—that is, just after having printed a character. Fig. 2 shows a vertical longitudinal section therethrough on the line 2 2 of Fig. 1, looking to the right. Fig. 3 shows a similar section through the upper part of the machine on the line 3 3 of Fig. 1, also looking to the right. Fig. 4 shows a vertical transverse section on the line 4 4 of Fig. 1, looking backward. Fig. 5 is a plan or top view of the type-wheel and its carrying-frame detached; and Fig. 6, a side elevation thereof, omitting the wheel. Fig. 7 is a plan view of the type-wheel-operating frame and key stop-bar detached. Fig. 8 is a diagrammatic side view illustrating the electrical and mechanical connections of the key-levers, type-wheel, and locking devices. Fig. 9 shows a detail view, partly in elevation and partly in section, of one of the type-wheels or key-stops in its forward position, Fig. 8 showing the corresponding parts in their normal or backward position. Fig. 10 shows a detail plan view of some of the parts shown in Fig. 8. Fig. 11 is a perspective view of the type-wheel locking-clutch or dog, and Fig. 12 a detail sectional view transverse to this dog and a portion of the type-wheel. Fig. 13 represents diagrammatically a vertical longitudinal section, illustrating the details of the mechanism for changing the throw of the type-wheel to change from capitals to small letters; and Fig. 14 is a diagrammatic plan view of the electrical circuits.

All the mechanism is shown as mounted in or upon a main frame A, having suitable bearings, brackets, and guides therefor. The characters, figures, letters, or symbols are arranged on the periphery of a type-wheel B, with the capitals and small letters preferably alternating, for a reason hereinafter explained. A series of notches h^2 in the side of the type-wheel receive a locking-dog H' , hereinafter described. The type-wheel is carried by a collar or sleeve b turning with but capable of sliding freely endwise on a shaft B' , mounted in bearing-screws b' in a carriage or frame B^2 , reciprocating longitudinally on guides B^3 B^4 on the main frame. The bearing-screws admit of the ready removal of the type-wheel and its shaft. Gears b^2 on the type-wheel shaft engage with racks c on a type-wheel-actuating frame C, provided with guides c' traversing the type-wheel carriage and having a greater range of reciprocation than that carriage. Laterally-projecting arms c^2 on the rear end of this carriage carry rods d , on which the armature-cores of the type-wheel-actuating magnets or solenoids D D' D^2 D^3 are mounted. These solenoids are shown as arranged parallel with each other and with the line of reciprocation of the type-wheel on opposite sides of the machine near its upper part, so as to secure di-

rect connection with the type-wheel-actuating frame reciprocated by them. They are also shown as arranged in pairs end to end, so that one armature-core serves for each pair of solenoids, and the cores are attracted by the solenoids, so as to move the frames with which they are connected in alternately-opposite directions as the current is shifted from one set of solenoids to the other. In the normal position shown in the drawings the circuit is through the rear solenoids D D' . When it is shifted through the front solenoids D^2 D^3 , the type-wheel-actuating frame C moves forward, while the type-wheel carriage B^2 remains stationary. The racks c consequently rotate the gears b^2 on the type-wheel shaft and turn the type-wheel. In order, however, to adapt the machine to print any characters desired, a stop-plate C' is mounted on the front end of the type-wheel-actuating frame C obliquely to its line of movement and is provided on its front edge with notches c^3 , one for each character on the type-wheel.

The usual finger-keys are arranged in any desired order at the front of the machine, a preferred arrangement for a special purpose being hereinafter indicated. A key-lever E on the left-hand of the key-board controls the printing of capitals. A corresponding key-lever E' on the opposite or right-hand side of the key-board controls the mechanism for releasing the type-wheel and retracting it to begin a new line and simultaneously feeding the paper correspondingly. The ordinary key-levers E^2 E^3 , &c., for printing the characters are shown as arranged horizontally and parallel with each other and as rocking on a common axis e.

In order to print several letters or short words rapidly by simultaneously depressing the necessary key-levers, the letters are arranged on the key-board from left to right, for a reason hereinafter apparent. For instance, Fig. 1 shows a key-board so arranged that the letters "W A S" run from left to right, also the letters "I N," while those "A N D" and "T H E" run from rear to front, though their levers run from left to right. The key-levers corresponding with any of these words can consequently be depressed simultaneously and be successively rapidly printed on the machine, as will be hereinafter explained. Each key-lever carries a stop-arm F, rocking vertically on a pivot f in a plane parallel with the key-lever and movable endwise vertically in a transverse guideway F² on the main frame wide enough to admit of a rocking or yielding motion of the stop-arm. Each stop-arm has steps f' f² on its head F', the lower one f² of which when the stop is elevated normally resting on the rear edge of the guideway F², while the upper one f' at the proper time engages with the corresponding notch on the stop-plate C'. Springs f³, connected with the lower end of the stop-arm F, tend to hold their upper ends

in their extreme backward positions and to hold the key-levers in their usual horizontal position. As a consequence of this organization, when a key is struck the rear end of its lever is lifted and its corresponding stop-arm elevated into the position shown by the dotted lines in Fig. 8—that is to say, with the second step f^2 resting on the upper rear bar of the guideway. The type-wheel-operating frame now advances until the proper notch c^3 of the oblique bar C' abuts against this stop, at which moment the relation of the parts is such that the character corresponding with the key pressed is presented by the wheel to the impression-cylinder. As the stops all lie in the same vertical plane across the machine, while the corresponding steps of the stop-arm are at gradually-increasing distances therefrom in a horizontal plane, it follows that the range of movement of the type-wheel-actuating carriage varies correspondingly with each letter. When the stop-plate C' abuts against the stop-arm F , its projecting edge underlies the upper step f' and forces the arm forward from the position shown in the dotted lines in Fig. 8 to that shown in Fig. 9. As the stop-arm moves forward it abuts against a cross-bar g , which I call a "shifter-bar," uniting two levers G , pendent from and swinging on another cross-bar g' near the upper end of the frame. Each of these levers G in turn is connected by a pivoted link G' with a corresponding arm G^2 , rocking on a pivot g^2 on the frame and normally held in a backward position by a spring g^3 . The arms G^2 are united at top by a cross-bar g^4 . This cross-bar is embraced by the forks h of an elbow-lever H , rocking horizontally on a vertical pivot h' on the frame and carrying a rearwardly-projecting arm H' , which at proper intervals enters the recesses h^2 in the side of the type-wheel, thus constituting a dog or clutch for steadyng the type-wheel or locking it in position while the character is being printed. The arm H' is tapered or beveled, as shown, so that at first it readily finds its way into the notches, and afterward, as the wheel is moved toward the impression-roller, the wider part of the arm completely fills a notch and holds the wheel steady. Set-screws f^4 serve to adjust the width of the guideway F^2 , and thus control the extent of rotation of the type-wheel by limiting the rearward movement of the shifter-bar g . When the forward movement of the type-wheel-operating frame C is thus stopped and the type-wheel locked, the circuits through all the solenoids and the front printing-magnets are broken and the circuit is closed through the rear printing-magnets $I^2 I^3$. The armature i of these magnets is mounted on an upright lever I^4 , rocking vertically on a pivot i' in a longitudinal plane parallel to the line of movement of the type-wheel. The upper end of this lever enters a loop j on a radius-bar J , rocking horizontally on a pivot j' on the left-hand side of the machine and connected by a

link-rod J' , pivoted to its free end, with the rocking pawl k of the ratchet k' on a spur-wheel K meshing with a spur-gear K' on a screw-shaft L , which controls the lateral feed of the type-wheel, as hereinafter described. Before doing this, however, I will recur to the means for reciprocating the type-wheel to print a character. The rocking armature-arm I^4 , above mentioned, is connected by a loop i with the type-wheel carriage B^2 , so that when this armature-lever moves backward it shoves this carriage before it and prints the character. As soon as this is done the circuit is restored through the front magnets $I^2 I^3$ and the carriage drawn forward.

I will now describe the means for moving the type-wheel laterally to space the characters. A block M slides freely endwise on the screw-shaft L , above mentioned. A forked rearwardly-extending arm m fits in a groove in the collar b of the type-wheel, thus connecting it with this block. A forward extension or plate M' connects this block M with a slide M^2 , movable endwise on a rock-shaft N . An arm n , capable of sliding freely on the rock-shaft and movable around its bearings in the slide M^2 , is provided with a tail-piece traversing a longitudinal groove in the rock-shaft, so that the arm n can turn both with and move laterally on the rock-shaft correspondingly with the type-wheel and traversing block M . That portion of the arm n which overlaps the screw-shaft L is correspondingly screw-threaded and normally held in contact therewith by a spring n' , so as to cause the type-wheel and block M to traverse step by step to space the printing, as hereinafter described. In thus traversing from left to right the block winds up a coiled spring M^3 , connected therewith by a cord or chain m' . When this block reaches the end of its traverse, the arm n is released from the screw-shaft L and the block M and type-wheel are retracted to the other side of the frame to commence a new line. A gage-stop L' on the left end of the screw-shaft regulates the point at which the line of print begins. A warning bell or alarm (not shown) indicates the approach of the type-wheel to the end of the line. Finger-levers m^2 , Fig. 4, pivoted on the plate M' and acting on the arm n , serve to detach the latter from the screw-shaft to move the type-wheel to the right or left by hand for ordinary adjustment. Regularly it is preferred to reset the type-wheel to begin a new line automatically. This I do as follows: At any moment when it is desired to reset the type-wheel the operator depresses a key E' on the right-hand side of the keyboard. This closes a circuit through a magnet O , actuating an armature-lever O' , rocking vertically and longitudinally on a pivot o at the back of the machine. The forward end of a link-rod O^2 , pivoted to the upper or free end of this armature-lever, is in turn pivoted to an elbow-lever O^3 , rocking on a pivot o' on the main frame. The short arm o^2 of this lever constitutes a dog, which acts on a

- crank-arm n^2 on the rock-shaft N and rocks it, so as to release the screw-arm n from the screw-shaft L. A spring-pawl n^3 , rocking horizontally on a pivot on the slide-block M, 5 inserts itself between this block and arm and holds the arm up. The spring M^3 then retracts the block to the left until the gage-stop L' abuts against the tail of the spring-pawl and withdraws it from under the screw-arm, 10 the spring of which immediately causes it to re-engage with the screw-shaft, when the parts are ready to begin a new line. In rapid work the type-wheel might acquire an impetus which would carry it too far for proper 15 registry, or the screw-shaft might feed it too far for proper spacing. I obviate these difficulties and insure proper spacing by providing a positive stop which controls the screw-shaft and type-wheel accurately. This I do 20 by mounting a cam-stop p' on the screw-shaft L, against which stop a detent p on the type-wheel-carrying frame B^2 abuts as the type-wheel moves away from the paper after printing a character.
- 25 In order to prevent the type-wheel from striking too hard against the printing-roller, a buffer is used, shown as consisting of a screw-rod R, passing through a bracket r on the main frame and through a lug r' on a 30 standard R' on the type-wheel-carrying frame B^2 , a spring r^2 being interposed between the bracket and lug. A roller r^3 on the arm traverses a guide-rail B^3 on the frame. These parts are duplicated on each side of the frame.
- 35 These rollers and guide-rails also support the rear end of the type-wheel-carrying frame, the front end of which is similarly guided and supported by rollers $a^3 a^4$, embracing guide-rails B^4 on the main frame.
- 40 The paper is fed downward over an inclined table S, between a feed-roll S', and an impressing-roller or printing-cylinder S² advanced step by step at the proper time to print a new line by means of a spring feed-pawl s' , pivoted on an arm s , rocking on an axis concentric with the roller and pivoted to the link-rod O², which releases the screw-shaft L, when the type-wheel retracts to begin a new line.
- 45 The inking-ribbon t, preferably used, is a narrow one held in proper position between the printing-roller and type-wheel by an arm or frame t', forming an extension of the type-wheel-hub controlling arm m. The ribbon is carried on reels T T', turning on vertical shafts on the main frame. The actuating-pawls t^2 of their feed-ratchets t^3 are so mounted on the type-wheel-carrying frame B^2 as to traverse the ribbon slightly across the line of 55 movement of the type-wheel at each reciprocation thereof. The pawls are provided with thumb-levers t^4 for releasing them or reversing the traverse of the ribbon, and the reels may be provided with the usual hand winding devices, which, however, are not shown in the drawings.

I will now describe the electrical part of the

apparatus and its circuit-connections, starting with the parts in their normal position shown in the drawings.

70

A switch U serves to connect or disconnect the battery, generator, or motor of the apparatus. I will first trace the solenoid-circuits. The current flows from the generator through a wire u to a binding-post V, as shown by the 75 full feathered arrow, Fig. 14. Thence, as shown by the unfeathered full-line arrows, it flows through the wires v v' to the contacts V' of the key-levers E². Thence it flows through the wire v² to the contact V², automatically controlled by the shifter-bar g. From the contact V² the current flows through the wire v³ through the left-hand rear solenoid D, thence by the wire v⁴ through the right-hand rear solenoid D', thence through the 80 wire v⁵ to the binding-post V⁵, thence through the wire u' to the generator. The current always flows through this circuit as long as the machine continues in its normal condition—that is, with the type-wheel carriage in its forward position. To throw this wheel forward to bring the proper letter into position and to lock the type-wheel preparatory to printing, the circuit is thrown through the front solenoids in the following manner by depressing 85 one of the key-levers E². The course of the current is shown by the dotted unfeathered arrows in Fig. 14. Beginning at the binding-post V, it first branches from the wire v, above described, by a wire W, from which a branch 90 w leads to a contact W', controlled by the key-lever E². Thence it passes by a wire w² through the front left-hand solenoid D², thence by a wire w³ to a contact W², controlled like its corresponding contact V², by 95 the shifter-bar g. From the contact W² wire w⁴ leads through the right-hand front solenoid D³ by a wire w⁵ to the main return-wire v⁵ and binding-post V⁵, as the other branch of the current did.

110

I will now describe the circuits through the printing-magnets, the one through the front set being shown by the full-feathered arrows, while that through the rear set is shown by the corresponding dotted arrows. Beginning 115 with the front set, a wire x, branching from the binding-post V, passes through a contact X, wire x², left-hand front printing-magnet I, the corresponding right-hand magnet I', and wire x³ to outgoing binding-post V⁵. An intermediate contact X' is also interposed in this circuit, for a purpose hereinafter explained. The rear magnet's circuit branches from the wire x at y' through a contact Y' and wire y² to a contact Y² on the lever G², 120 controlled by the shifter-bar g, the same one controlling the solenoid's contacts V² W², as above described. From contact Y² the circuit passes through the wire y³, left-hand rear printing-magnet I², corresponding right-hand magnet I³, and wire y⁴ to binding-post V⁵.

120

I will now describe the circuit-connections by which the type-wheel is released from the screw, so as to enable it to run back to com-

mence a new line and at the same time to feed the paper to commence a new line. A key-lever E' on the right-hand side of the key-board when depressed closes a contact Z , 5 Fig. 14, the circuit through which is as follows: A wire z , branching from the incoming binding-post V , passes through the contact Z , wire z' , magnet O , wire z^2 , and return-wire v^3 to the outgoing binding-post V^5 .

10 From the foregoing description it will be seen that the entire apparatus is actuated by electricity, thrown into operation either automatically or simply by depressing the keys.

The apparatus operates as follows, starting 15 from the normal position shown in the drawings—that is, with the type-wheel-actuating carriage in its extreme rearward position, with the type-wheel in its forward position and clear of the printing-roller, unlocked 20 and free to turn, its actuating gear-wheel b^2 engaging with the forward part of the rack c of the actuating-carriage C . In this position the contact V^2 is closed and the rear solenoids $D D'$ are consequently in circuit. The contact X is also closed and the circuit flows 25 through the front set of printing-magnets $I I'$. If now a key-lever E^2 be depressed, the circuit is thrown through the front solenoids $D^2 D^3$ and draws forward the type-wheel-actuating 30 frame C , while the type-wheel carriage B^2 is held stationary by abutting against suitable stops on the frame. Meanwhile the depression of the key-lever has thrown up its corresponding stop-arm F in its guideway F^2 , 35 so that its lower step f^2 rests on the upper rear edge thereof directly in the path of the notched stop-plate C' . As this plate moves forward with the type-wheel-actuating frame, one of its notches c^3 , corresponding with the 40 stop which has been elevated, slides under the upper step f' of the stop-arm F and shoves it forward from the position shown in the dotted lines in Fig. 8 to the position shown in Fig. 9, the stop-arm now abutting against the front 45 side of its guideway F^2 . A bar q , which I term a "contact-bar," rests upon the top of the key-levers and is connected by radius-bars Q with the axis e , on which the key-levers rock in such manner that the contact-bar q while resting upon the key-levers is free 50 to rise and fall therewith. As a consequence of this organization, when a key is depressed and the rear end of its lever is thrown up it lifts the contact-bar q and a pendent arm q' 55 connected therewith. This opens the spring-contact V' , which this pendent arm normally holds closed, and thus breaks the circuit through the rear solenoids. At the same time a corresponding pendent arm q^2 , likewise connected 60 with this contact-bar, closes the spring-contact W' , normally held open, and thus throws the circuit through the front solenoids. As the stop-arm F is shoved forward by the 65 stop-plate C' it carries with it the shifter-bar g , which in turn, through the swinging levers G and pivoted links G' , throws forward the arms G^2 , carrying the cross-bar g^4 , which actu- 70 ates the dog H and interlocks it with the type-wheel. Previously to this being done, however, the type-wheel has revolved during the forward movement of its actuating-carriage to bring the letter corresponding to that of the key depressed into proper position for printing and the dog locks it securely in this position. This forward movement of the 75 shifter-bar g actuates the links and levers G G' , &c., and simultaneously opens the contacts V^2 W^2 of both solenoid-circuits. This movement at the same time opens the contact X by allowing hook p^3 to drop over 80 pin p^4 , when spring p^6 draws lever P backward. This same forward movement of shifter-bar g and lever G^2 closes contact Y^2 and sends current through the rear printing-magnets, which attracts the armature i on lever I' , 85 connected with type-wheel carriage B^2 and with radius-bar J , by which the screw-shaft L is actuated. This attraction of the armature i also carries the type-wheel carriage with it and prints a letter. This backward movement 90 of the type-wheel carriage at the moment the type-wheel strikes the paper opens the contact Y' of the rear printing-magnets' circuit and simultaneously closes the one X' through 95 the front printing-magnets by means of a pin x^6 , acting on arm x^4 , pendent from slide-bar x^7 , thus drawing the type-wheel carriage forward and away from the paper, by which forward motion the pin x^6 , acting on arm x^5 , pendent from slide-bar x^7 , reverses the position 100 of the contacts X' and Y' and puts them in their normal position—viz., Y' closed and X' open. Simultaneously with this movement the radius-bar J , through its link J' and pawl k , turns the screw-shaft L . The cam l on this 105 shaft acts on the upper end of the three-armed lever P , rocking on pivot p^3 , and releases hook p^3 on said lever from pin p^4 on the arm G^2 , with which it is held in engagement by spring p^6 . As soon as lever P is released, as above 110 described, the spring g^3 retracts the arm G^2 , thus releasing dog H' from contact with the type-wheel. In its forward movement the arm G^2 strikes against the downwardly-projecting arm p^5 of the lever P and causes the 115 hook p^3 to positively engage with the pin p^4 should the spring not act efficiently. This arm p^5 also forces G^2 backward in case the spring g^3 does not act efficiently when pin p^4 is released by action of cam l against lever P 120 and raising hook p^3 , thus positively disengaging dog H' from contact with the type-wheel. This forward movement of lever P closes the contact X of the front printing-magnets' circuit before the circuit is broken at X' by the 125 movement of type-wheel carriage B^2 , actuating slide-bar x^7 by a pin x^6 against the pendent arm x^5 , as above described, thus holding the type-wheel carriage forward in its normal position. When the backward movement of 130 lever G closes the contacts W^2 and V^2 , the circuit through the rear solenoids is closed in case no key is depressed, thus drawing the type-wheel-actuating frame C to the rear in

its normal position; but if one or more keys are depressed, then the circuit through the front solenoids $D^2 D^3$ is closed, and the type-wheel-actuating frame is drawn forward until 5 stopped by a stop-arm F, when the operation of printing is repeated until the last stop-arm is down. When the type-wheel-actuating frame C is drawn forward by the action of the front solenoids $D^2 D^3$ and strikes a stop-arm F, it is locked with the type-wheel carriage B² by means of the action of lever H' and intervening mechanism, and both frames C and B² are drawn backward to print by the 10 action of printing-magnets I² I³. As the type-wheel-actuating frame C moves backward in the act of printing, carrying with it the stop-plate C', the latter releases the stop-arm previously held up by it and allows it to drop to its normal position. The backward movement 15 of the arm G² also carries the shifter-bar g back to its normal position. Striking the same key in succession or holding it down would of course cause that character to be reprinted.

20 25 The angular or oblique arrangement of the stop-plate relatively to the line of stops enables me to save the time consumed in traversing the type-wheel-actuating carriage its full distance, and also enables me to strike a number of keys simultaneously—say, for instance, the word "and." When the stops corresponding with these characters are elevated, the stop-plate comes in contact with the first one, the type-wheel is locked, which 30 also locks together the type-wheel carriage B² and the type-wheel-actuating frame C, the circuits are automatically completed through the rear printing-magnets, thus drawing both frames backward, which releases the stop corresponding with the first letter of the word. This backward movement closes the contacts of the front printing-magnets and breaks those of the rear printing-magnets at the moment of printing, which moves both frames forward. This forward movement closes the 35 contacts through the front solenoids as soon as the type-wheel and frames are unlocked by the revolution of the screw-shaft L, and runs the type-wheel-actuating frame forward again until it meets the next stop, without the necessity of its returning to its normal position after each letter printed. This operation is continued automatically as long as one or more stops remain elevated. When the 40 last stop drops, the parts resume their normal position—viz., the type-wheel-actuating frame to the rear, the type-wheel-carrying frame to the front.

Under the organization shown the capitals 45 alternate with their corresponding small letters on the type-wheel. When working full-stroke, the type-wheel carriage prints small letters only. In order to print capitals, I provide a separate key E, marked "upper-case," 50 on the left side of the key-board. This key carries a stop e', which stands normally out of the way of the type-wheel carriage B², but

which when the key is depressed abuts against said carriage and stops it when it has made, say, one-half of its forward movement. This 70 brings the capital letter on the type-wheel in proper position for printing. To retract the type-wheel to begin a new line and at the same time feed the paper forward, a key E' on the right side of the key-board is depressed. This closes the contact Z through the printing-magnet O, drawing its armature O' forward, and through the link-rod O² and elbow-lever O³ depresses the dog o², bearing on the crank-arm n², and rocks it, thus rocking the screw-arm n and releasing it from the screw-shaft L, when the spring M³ retracts the type-wheel to the proper position to begin a new line. The paper is simultaneously fed forward on the roller S² by the pawl s', connected with the link-rod O².

The type-wheel is formed with one or more spaces b² between some of the types, and by corresponding keys the operator may advance the type-wheel across the page the desired number of spaces without printing, also to form space after a word by striking space-key simultaneously with last letter of a word.

Having thus described my improved electric type-writer, what I claim therein as new and as of my own invention, is—

1. The combination, substantially as hereinbefore set forth, of a main frame, a type-wheel carriage, traversing longitudinally 100 guides therein, a type-wheel movable endwise on but turning with a shaft mounted in bearings in said carriage, a type-wheel-actuating frame traversing longitudinally guides on the carriage parallel therewith, racks on this actuating-frame engaging with gears on the type-wheel shaft, and electro-magnetic apparatus for reciprocating the actuating-frame and thereby turning the type-wheel.

2. The combination, substantially as hereinbefore set forth, of a main frame, a carriage traversing longitudinally guides therein, a type-wheel carried by a shaft mounted in said carriage, a type-wheel-actuating frame traversing longitudinally guides on this carriage, 115 racks on this frame engaging gears on the type-wheel shaft, a dog engaging the type-wheel at suitable intervals to lock the carriage and actuating-frame together, and electro-magnetic apparatus for reciprocating them 120 when thus interlocked.

3. The combination, substantially as hereinbefore set forth, of a main frame, a carriage traversing longitudinally in guides therein, a type-wheel carried by a shaft mounted in 125 said carriage, a type-wheel-actuating frame traversing longitudinally guides in this carriage and parallel therewith, rack on this frame engaging gears on the type-wheel shaft, a dog engaging the type-wheel at suitable intervals to lock the carriage and actuating-frame together, electro-magnetic apparatus for reciprocating both the carriage and frame together when thus interlocked, and means 130

for automatically unlocking them to allow the type-wheel to turn by the forward movement of the actuating-frame.

4. The combination, substantially as hereinbefore set forth, of a main frame, a carriage traversing guides therein, a type-wheel carried by a shaft mounted in said carriage, a type-wheel-actuating frame sliding longitudinally parallel with said carriage on guides therein, racks on this frame engaging gears on the type-wheel shaft, solenoids mounted on the main frame, armature-cores therefor connected directly with the actuating-frame, a stop-plate also carried by this frame, a key-lever, a stop thrown thereby across the path of the stop-plate, a locking-dog engaging with the type-wheel, and mechanism for releasing it.

5. The combination, substantially as hereinbefore set forth, of a main frame, a carriage traversing longitudinally guides therein, a type-wheel mounted therein, an actuating-frame traversing longitudinally guides in said carriage, a stop-plate on this frame, a key-lever, a stop thrown across the path of this stop-plate thereby, a dog engaging with the type-wheel, and mechanism to unlock the dog.

6. The combination, substantially as hereinbefore set forth, of a main frame, a carriage traversing guides therein, a type-wheel mounted therein, an actuating-frame traversing guides therein, means for rotating the type-wheel by the differential movements of its carriage and actuating-frame, a stop-plate on this frame, a key-lever, a stop thrown across the path of this stop-plate thereby, a locking-dog engaging with the type-wheel, a shifter-bar actuated by the stop, link connections between this bar and the locking-dog, a spring-latch or locking-lever which holds the dog in position, and the cam which releases the latch at the proper moment.

7. The combination, substantially as hereinbefore set forth, of a main frame, a carriage traversing therein, a type-wheel mounted in the carriage, an actuating-frame traversing guides in the carriage, gearing for rotating the type-wheel by the differential movement of this carriage and frame, a locking-dog engaging with the type-wheel, a spring-latch which holds this dog in its locked position, a releasing-cam actuating the spring-latch, and an arm on said latch positively actuated by the mechanism which locks the dog to insure the fastening of the spring-latch.

8. The combination, substantially as hereinbefore set forth, of a main frame, a carriage traversing guides therein, a type-wheel mounted therein, an actuating-frame traversing guides therein, a stop-plate carried by this frame oblique to its line of movement, a series of key-levers, a series of stops arranged transversely across the machine in the same vertical plane, each actuated by its respective key-lever, and means for reciprocating

the stop-plate and for varying its range of movement according to the stop interposed.

9. The combination, substantially as hereinbefore set forth, of a reciprocating carriage, a type-wheel mounted therein, an actuating-frame traversing said carriage, a stop-plate on this frame oblique to its line of movement, a series of key-levers, stops traversable thereby athwart the line of movement of the stop-plate, a shifter-bar actuated by the stops, link connections actuated by this bar, a locking-dog actuated thereby, and electro-magnetic devices, also actuated by said link connections, regulating the movement of the type-wheel carriage and actuating-frame.

10. The combination, substantially as hereinbefore set forth, of a reciprocating type-wheel carriage or actuating frame, a stop-plate carried thereby, a series of key-levers, stops traversed thereby athwart the line of movement of the stop-plate, electro-magnetic devices for reciprocating said actuating-frame, and circuit-controlling devices actuated by the key-levers controlling said mechanism.

11. The combination, substantially as hereinbefore set forth, of a guideway, stops movable therein, a notch or step on each stop, a spring tending to engage the notch with the guideway when the stop is elevated, a stop-plate which releases the step from engagement with the guideway, and a type-wheel rotated by the stop-plate.

12. The combination, substantially as hereinbefore set forth, of a type-wheel movable laterally on its shaft, a feed-screw shaft, a slide-block thereon movable with the type-wheel, a rock-shaft, a screw-arm thereon interlocking with the slide-block and screw-shaft, a crank-arm on the rock-shaft, a dog acting thereon to release the screw-arm, electro-magnetic devices controlling link connections actuating the dog, and a spring to retract the type-wheel when released from the screw-shaft.

13. The combination, substantially as hereinbefore set forth, of a type-wheel, its reciprocating carriage, its separate reciprocating actuating-frame, type-wheel-locking mechanism carried by an independent frame, and means for actuating the locking mechanism from the actuating-frame.

14. The combination, substantially as hereinbefore set forth, of a reciprocating stop-plate, stops traversing its path, a shifter-bar actuated by the pressure of the stop-plate on the stops, a type-wheel, a dog interlocking therewith, and link connections between said shifter-bar and dog.

15. The combination, substantially as hereinbefore set forth, of a type-wheel, its carriage, its actuating-frame, a stop-plate carried thereby, yielding spring-stops intercepting the path of the stop-plate, a shifter-bar actuated by the stop-plate and stops, a dog interlocking with the type-wheel, link con-

nctions between the shifter-bar and dog to lock the type-wheel, and means for automatically releasing said dog.

16. The combination, substantially as hereinbefore set forth, of a type-wheel, a feed-screw shaft, mechanism connecting the wheel and shaft to feed the latter laterally, a laterally-moving locking-dog, link connections actuating it, and a cam on the feed-screw shaft to release the dog.

17. The combination, substantially as hereinbefore set forth, of a type-wheel, a rocking locking-dog engaging therewith, a vibrating arm actuating said dog, a pin or stop carried by the arm, a spring-actuated notched locking-lever engaging therewith to hold the dog in the proper position, and a cam on the feed-screw shaft to release the dog.

18. The combination, substantially as hereinbefore set forth, of a reciprocating type-wheel carriage, a type-wheel mounted therein, a feed-screw shaft for moving the type-wheel laterally, connections between the type-wheel and screw-shaft, a stop on the latter, and a detent on the carriage abutting against the stop to lock the type-wheel positively at the proper moment.

19. The combination, substantially as hereinbefore set forth, of a main frame, a carriage reciprocating in guides therein, a type-wheel in this carriage, a type-wheel-actuating frame reciprocating in guides on the carriage, gearing connecting the carriage and frame, means for reciprocating the actuating frame and thereby rotating the type-wheel, separate means for actuating the carriage, and means for locking the type-wheel and actuating-frame so as to print a letter by actuating the type-wheel carriage.

20. The combination, substantially as hereinbefore set forth, of a type-wheel, its carriage, its actuating-frame, a feed-screw shaft, connections between it and the type-wheel, ratchet-gearing for rotating said shaft intermittently, and links connecting such gearing and carriage so as to feed the type-wheel laterally after each reciprocation of the type-wheel.

21. The combination, substantially as hereinbefore set forth, of a type-wheel having capital and small letters arranged alternately on its periphery, a reciprocating type-wheel carriage, a key-lever, and a stop connected therewith to limit the range of movement of the type-wheel when capitals are to be printed.

22. The combination, substantially as hereinbefore set forth, of a type-wheel, its carriage, a feed-screw shaft, a ratchet-feed and link connections between the feed-screw shaft and carriage, a rock-shaft, a laterally-sliding frame connecting the type-wheel, screw-shaft, and rock-shaft, a pivoted spring-arm carried by the rock-shaft and carrying a screw engaging with the screw-shaft, a crank-arm on the rock-shaft, a dog acting thereon, and link connections for rocking the shaft to release

the actuating-arm from the screw-shaft when the type-wheel is to be retracted to commence a new line.

23. The combination, substantially as hereinbefore set forth, of a type-wheel, its carriage, a feed-screw shaft, a ratchet-feed and link connections between said screw-shaft and carriage, a rock-shaft, a laterally-sliding frame connecting the type-wheel, screw-shaft, and rock-shaft, a pivoted spring-arm carried by the rock-shaft and carrying a screw engaging with the screw-shaft, a crank-arm on the rock-shaft, an impression-cylinder, its paper-feeding pawl, and link connections for simultaneously actuating the pawl and turning the rock-shaft so as simultaneously to release the actuating-arm from the screw-shaft when the type-wheel is to be retracted and simultaneously to feed the paper by actuating the pawl.

24. The combination, substantially as hereinbefore set forth, of a type-wheel, its reciprocating carriage, a type-wheel-actuating frame, mechanism carried thereby for feeding the type-wheel laterally therein, a generator of electric currents, circuit-connections, key-levers controlling them to reciprocate the type-wheel-actuating frame, a stop-plate on said frame, and stops actuated by the key-levers which control other circuit-connections, and mechanism actuated by said circuit-connections which prints a character and actuates the type-wheel-feeding mechanism.

25. The combination, substantially as hereinbefore set forth, of a type-wheel, its reciprocating carriage, a reciprocating type-wheel-actuating frame, gearing for reciprocating the type-wheel from the actuating-frame, a source of electric energy, mechanism actuated therefrom to reciprocate the actuating-frame, and automatic circuit-shifting devices operated by the actuating-frame to reverse its movements at the proper time.

26. The combination, substantially as hereinbefore set forth, of a main frame, a type-wheel, its carriage reciprocating in guides in the main frame, a type-wheel-actuating frame reciprocating in guides on the carriage, solenoids arranged end to end in pairs on opposite sides of the main frame, (the solenoids of each pair being oppositely wound,) their armature-cores connected directly with the actuating-frame, and circuit-connections by which the current is alternately shifted from one set of solenoids to the other to rotate the type-wheel.

27. The combination, substantially as hereinbefore set forth, of a type-wheel, its carriage reciprocating in guides on the main frame, a vibrating armature connected directly with this carriage, electro-magnets on opposite sides of said armature, and circuit-connections automatically controlled by the reciprocation of the frame alternately to shift the current through the magnets to print a character and to retract the type-wheel from the impression-cylinder.

28. The combination, substantially as here-

inbefore set forth, of a main frame, a type-wheel, its carriage, a type-wheel - actuating frame reciprocating in guides therein, solenoids arranged end to end in pairs on the 5 main frame, (the solenoids of each pair being oppositely wound,) their armature-cores connected with the actuating-frame, key-levers, a contact-bar or rocking frame resting thereon, and circuit-controlling devices carried by 10 the contact-bar so as to shift the current from one set of solenoids to the other on the depression of a key.

29. The combination, substantially as hereinbefore set forth, of a type-wheel, its reciprocating carriage, electro-magnetic devices 15 actuating the latter, a reciprocating type-

wheel-actuating frame, electro-magnetic devices operating it, a stop-plate carried by this frame, a yielding stop intersecting the path of the stop-plate, a shifter bar or frame actuated by the stop-plate and interposed stop, circuit-connections, and circuit-controlling devices actuated by the reciprocation of the type-wheel carriage and actuating-frame and of the shifter-bar to shift the current through 20 both sets of actuating-magnets.

In testimony whereof I have hereunto subscribed my name.

EDWARD J. SILKMAN.
